UNITED STATES PATENT OFFICE

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 13,523, dated January 16, 1883.

Application filed November 18, 1882. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an ornamented letter shaded upon the right and below by a lighter line. The upper half of the face of the letter is ornamented by a series of light lines. In many of the letters the light

shaded line terminates in a small heavy dot. 15 In the A, H, N, Q, and R the right-hand portion and tail of the letter is extended below the line, and in the C, E, G, H, and S the upper right-hand termination of the letter is inclined.

Having now described my invention, I claim 20 as new--

The design for a font of printing-type, as shown and described.

WM. W. JACKSON.

In presence of—

C. F. HUCH,
HERMAN METIUS.
